NURSERY UTILITY TRAY

David Honig, Brooklyn, N. Y.

Application October 23, 1948, Serial No. 149,259

Term of patent 7 years

(Cl. D4—3)

To all whom it may concern:

Be it known that I, David Honig, a citizen of the United States, residing at Brooklyn, New York, in the county of Kings and State of New York, have invented a new, original, and ornamental Design for a Nursery Utility Tray, of which the following is a specification, reference being had to the accompanying drawing, forming a part thereof.

In the drawing:

Fig. 1 is a front perspective view of a nursery utility tray, showing my new design;

Fig. 2 is a rear perspective view of the same;

Fig. 3 is a longitudinal vertical sectional view taken on the line of 3—3 of Fig. 2; and

Fig. 4 is a transverse vertical sectional view taken on the line 4—4 of Fig. 2.

I claim:

The ornamental design for a nursery utility tray, as shown.

DAVID HONIG.
